UNITED STATES PATENT OFFICE.

IRA H. SPENCER, OF WEST HARTFORD, CONNECTICUT, ASSIGNOR TO THE SPENCER TURBINE CLEANER COMPANY, OF HARTFORD, CONNECTICUT, A CORPORATION OF CONNECTICUT.

APPARATUS FOR PROPELLING FLUIDS.

1,061,205.

Specification of Letters Patent.

Patented May 6, 1913.

Application filed August 12, 1912. Serial No. 714,513.

To all whom it may concern:

Be it known that I, IRA H. SPENCER, a citizen of the United States, and a resident of West Hartford, in the county of Hartford and State of Connecticut, have invented a new and Improved Apparatus for Propelling Fluids, of which the following is a specification.

My invention relates to the class of devices above named, and an object of my invention, among others, is to provide a device of this class that while possessing self-balancing characteristics, or characteristics by which a running balance is preserved, shall at the same time be firm and stable in its construction.

One form of device embodying my invention and in the construction and use of which the objects herein set out, as well as others, may be attained is illustrated in the accompanying drawings, in which—

Figure 1 is a view in side elevation, partially in section, of an apparatus more especially adapted for propelling air, with parts broken away to show construction, and illustrating characteristic features of my invention. Fig. 2 is a view in crosswise section on a plane denoted by dotted line 2—2 of Fig. 1.

In the construction and operation of apparatus embodying parts rotating at high speed, and especially those in which these rotating parts have considerable surface area located laterally to the axis of rotation, a difficulty has been encountered in preserving a running balance, as it is frequently found that such apparatus provided with a static balance will, owing to various conditions of operation, be thrown out of balance when rotated at high speeds. This is especially true of steam turbines, dynamos, air turbines and the like, and more especially with respect to air turbines, as such a device when constructed to run in equilibrium in the open air will be frequently found to be unbalanced when placed in a casing, for the reason that the action of the air on the fans is different when inclosed than when running in the open air, and while my invention is susceptible of embodiment in any of the various devices in which the faults above mentioned may occur, I have selected an air turbine for the purpose of illustrating and describing my invention herein.

In the operation of air turbines or fans, and especially when these are inclosed within a casing, the effects of the air currents are such as to create various conditions with respect to the forces acting upon the disks, with the effect that a disk which may be perfectly balanced at one speed will be thrown out of balance at another speed, and in the case of several disks mounted upon a shaft, the conditions which will affect one disk at a certain point in one way will affect another disk at the same point in a different way. These faults are especially noticeable when parts intended to be rotated at high speed are attaining such speed, as frequently during such time, "critical speeds" occur causing objectionable vibration which is frequently excessively dangerous.

The device illustrated herein obviates the difficulties with respect to the balance of the rotating parts at all times whether running at high or low speeds, and at the same time the parts are sufficiently rigid to be firm and stable. Such a device includes a casing supported on a base 6 and having a top plate 7, the base and top plate being connected as by rods 8. A motor 9 may be supported on the top plate 7 as a means for driving the apparatus. A projection 10 in which the inlet opening is located extends from the top of the shell or casing 5 and an exhaust opening may be located in the projection 11 near the bottom of the shell or casing. All of the parts thus far described may be of any suitable form and construction and further detailed description is therefore deemed unnecessary.

A shaft 12 extends through the casing longitudinally thereof, this shaft being suitably connected with the motor 9 and arranged in any suitable manner as to its bearing. This shaft will be sufficiently rigid to afford a firm support for the rotating parts, including fan hubs 13 securely fastened to the shaft and rigidly constructed and fan disks 14 securely fastened to the fan hubs. In order that these disks may accommodate themselves to various conditions that may exist within the casing and may be at all times so positioned with respect to the shaft 12 as to preserve a perfect running balance the disks are made flexible so that they will yield to any force which would tend to throw the rotating parts out of bal-

2
ance, such yielding function being illustrated to an exaggerated extent perhaps in dotted outline in Fig. 1 of the drawings. Blades 15 are secured to the disks 14 in any 5 suitable manner, these blades being of such construction that the current of air will be forced radially outward along the surface of the disk 14 to the periphery thereof and whence the air travels inwardly toward the 10 center passing through the openings 16 in diaphragms 17.

In order that the flexibility of the structure may be increased the heels 18 of the 15 blades are located at some distance from the periphery of the fan hubs 13 to permit a yielding action at this point, and deflectors 19 may also be employed to direct the air currents toward the openings 16.

It will thus be seen that if conditions as 20 to the air currents or other causes shall exist to create a force tending to displace the disks and thus create unbalanced conditions as to the rotating parts, the disks will flex under such force and thus preserve the balance of the rotating parts and avoid the 25 difficulties hereinbefore referred to, the structure being in fact a "self-balancing" structure.

The best commercial practice at the present 30 time for balancing high speed rotating parts is in subjecting them to operation in a dynamic balancing machine, but this is not applicable to a turbine blower, owing to the varying conditions of air currents, as hereinbefore set out, but my invention 35 provides means for readily and effectively overcoming the difficulties not only in the use of inclosed rotating parts, but in the

use of all rotating structures of a character contemplated herein.

While I have shown and described herein one form of mechanism for accomplishing the results sought to be obtained by my invention, it may be present in a structure differing somewhat from that herein illustrated and described.

I claim—

1. A casing, a rotatable shaft extending within the casing, disks of a flexible character secured to said shaft and arranged to 50 flex in a direction longitudinally of the shaft, said disks having means to support a blade radially thereon.

2. A casing, a rotatable shaft of rigid material located within the case, a disk of flexible material secured to said shaft and constructed to flex in a direction longitudinally thereof, and blades secured to said disk.

3. A casing, a shaft of rigid material located within the casing, means for rotating 60 the shaft, a disk of flexible material firmly secured to the shaft and constructed to flex in a direction longitudinally of the shaft, and blades secured to the face of the disk and extending radially thereof.

4. A casing, a shaft of rigid material located within the casing, means for rotating the shaft, a series of disks of flexible material firmly secured to the shaft and constructed to flex in a direction longitudinally 70 thereof, and blades secured to the faces of said disks.

IRA H. SPENCER.
